[57] CLAIM

The ornamental design for a frame for tile cutter, as shown and described.

DESCRIPTION

FIG. 1 is a perspective view of a frame for tile cutter showing my new design;

FIG. 2 is a front elevational view thereof;

FIG. 3 is a front elevational view with the arm in the raised position;

FIG. 4 is a fragmentary perspective of the cutting wheel assembly shown separately for clarity of illustration;

FIG. 5 is an enlarged fragmentary front elevational view with the arm lowered;

FIG. 6 is an enlarged fragmentary front elevational view with the arm raised.

The elements in broken lines are shown for illustrative purposes only and form no part of the claimed design.
